UNITED STATES PATENT OFFICE.

JOHN LEO STRANDBERG AND LARS ERIK JULIUS BLOMBERG, OF KANSAS CITY,
MISSOURI.

PNEUMATIC JACK.

Application filed July 21, 1923. Serial No. 652,961.

To all whom it may concern:

Be it known that JOHN L. STRANDBERG and LARS ERIK JULIUS BLOMBERG, citizens of the United States, residing at Kansas City, in the county of Jackson and State of Missouri, have invented certain new and useful Improvements in Pneumatic Jacks, of which the following is a specification.

In carrying out the present invention it is our purpose to provide a highly novel and useful form of pneumatic jack that is primarily but not specifically adapted for use in conjunction with the raising of concrete forms.

The primary object of our invention is to substantially improve over the usual screw types of jacks now employed for this purpose, our invention being extremely simple of construction and efficient in operation, 20 the same comprising relatively few parts, these co-related in such a manner as to reduce the possibility of disarrangement to minimum.

An additional object of this invention is the provision of such a pneumatic jack wherein the concrete forms may be slowly raised through the medium of air pressure, the nature of this jack being such as to permit its manufacture, marketing and operation at a minimum expenditure.

With the above and other objects in view as the nature of the invention is better understood from the following specification and accompanying drawings the same comprises the construction, combination and arrangement of parts hereinafter set forth and claimed.

In the drawings wherein like reference characters indicate corresponding parts throughout the several views, and wherein:

Figure 1 is a side elevation of our improved jack.

Figure 2 is a detailed vertical transverse cross-section thereof,

Figure 3 is a detailed transverse cross-section taken substantially upon the line 3-3 of Figure 1 and looking downwardly in the direction of the arrows,

Figure 4 is the top plan view of the jack, 50 and

Figure 5 is a side elevation of our improved jack, the same being shown as associated with a concrete form.

Now having particular reference to the drawings our novel pneumatic jack embodies the provision of a cylinder 5 opened at its lower end and formed centrally with an open ended tube 6 through which extends the well known climbing rod 7, the said cylinder 5 having free up and down movement upon said rod.

Adjacent the upper end of this cylinder 5 the same is internally formed with a shoulder 8 for limiting the upward sliding movement of a piston 9 that has free rectilinear movement within said cylinder 5, this piston 9 being formed upon the upper end of a hollow piston rod 10 that encircles said tube 6 of the cylinder 5 as clearly shown in Figure 2.

The upper end of said cylinder 5 is flanged at 11 and secured thereto through the medium of bolts or other suitable securing means 12 is the base 13 of an upwardly extending relatively elongated sleeve 14 that encircles said climbing rod 7 and has free sliding movement thereon. This sleeve 14 carries a pair of set screws 15 that are adapted to be forced into engagement with the climbing rod 7 for purposes and in a manner hereinafter more fully described.

Surrounding this climbing rod 7 at a point directly beneath the lower end of the tubular piston rod 10 is a collar 16 that also has free sliding movement upon said rod 85 and carries a pair of set screws 17 that are adapted to be forced into engagement with said rod for maintaining said collar in fixed relation thereto.

Leading into the upper end of the cylinder 5 at a point above the piston 9 is one end of a compressed air pipe 18, this pipe having communication with a suitable source of compressed air. This cylinder 5 is also provided at its upper end with a valved exhaust 95 19 and in actual practice, a concrete form A, Figure 5, is secured to the upper end of this cylinder 5 through the medium of rod 20 and whenever it is desired to slowly raise said concrete form A, air of a pre- 100

determined pressure is injected into the upper end of the said cylinder for consequently forcing the same upwardly upon the piston 9, it being of course understood 5 in this connection that the collar 16 has fixed relation to the climbing rod 7. For preventing total disengagement of this piston from the cylinder the said cylinder 5 is provided adjacent its lower end with discharge orifices 21 whereby when said piston passes therebeneath, the air will be discharged through said orifices.

After the concrete form has been moved upwardly to the limit of movement of the 15 jack the air is turned off. The set screws 15 and the sleeve 14 are now tightened and the air in the cylinder is let out through the exhaust, after which the set screws 17 of the collar 16 are released and the same 20 moved upwardly upon the climbing rod, consequently forcing the piston 9 upwardly within the cylinder 5. After this operation has been completed the set screws 15 are released and the set screws 17 tightened and 25 the air again admitted to the cylinder 5 for consequently raising the form still further upwardly.

In view of the above description numerous 30 advantages together with the specific operation of our device will be at once apparent to those skilled in the art and even though we have herein set forth the most practical embodiment of the invention with which we are at the present time familiar, it is nevertheless to be understood that minor changes 35 may be made therein without departing from the spirit and scope of the invention as claimed.

Having thus described our invention, 40 what we claim as new and desire to secure by Letters Patent is:—

1. In a pneumatic jack of the character described a cylinder attached at one end to the article to be raised and freely vertically 45 movable upon a climbing rod, a piston freely movable within said cylinder and adapted to be attached to said climbing rod, and an air inlet and exhaust for said cylinder above said piston.

2. In a pneumatic jack as set forth, a climbing rod, a cylinder freely vertically movable upon said climbing rod and adapted to be attached the article to be raised, a piston movable within said cylinder and 55 adapted to be detachably secured to said climbing rod, said cylinder being provided with a compressed air inlet and exhaust above said piston, and means for securing said cylinder to said climbing rod when the same has been forced upwardly thereon by the air pressure injected into said cylinder.

3. In a pneumatic jack as set forth, a climbing rod, a cylinder freely movable upon 60 said rod and adapted to be secured to the

article to be raised, a piston freely rectilineally movable within said cylinder and adapted to be attached to said climbing rod in the raising of said article, said cylinder being provided with a compressed air inlet and exhaust, and means for securing said cylinder to the rod after the same has been moved upwardly thereon.

4. In a pneumatic jack as set forth, a climbing rod, a cylinder freely movable upon said rod and adapted to be attached to the 75 article to be raised, a piston freely movable within said cylinder, adjustable means for preventing downward movement of said piston upon said climbing rod, an air inlet and exhaust for said cylinder above said piston, said cylinder being formed with openings adjacent its lower end for permitting of the escape of the air therefrom after the cylinder has been raised upwardly to a position above said piston, and means for securing said cylinder to said climbing rod after the same has been moved upwardly thereon.

5. A device of the class described, including a pair of slidably interfitting members 90 movable on a climbing rod, means on the rod for securing each of the respective members against movement thereon, and means for admitting fluid under pressure between said members for effecting a relative sliding 95 movement thereof.

6. A device of the class described, including a pair of relatively slidable telescopically arranged members having a closed chamber formed therebetween, and movably mounted on the rod, means for admitting fluid under pressure to said chamber for effecting a relative sliding movement between the members, and means for securing each member against movement on the rod. 100

7. A device of the class described, including a pair of relatively slidable telescopically arranged members having a closed chamber formed therebetween, and movably mounted on the rod, means for admitting fluid under pressure to said chamber for effecting a relative sliding movement between the members, means for securing said member against movement on the rod, and means for limiting the movement of the 110 members when actuated by fluid pressure.

8. A device of the class described including a pair of relatively slidable members movable on the rod, means for preventing movement of either of said members on the rod, and means for admitting fluid under pressure to said members for effecting a relative sliding movement therebetween.

9. A device of the class described comprising a pair of relatively slidable interfitting members movably mounted on a rod, means for preventing movement of either of said members on the rod, and means for pro- 125

ducing a relative sliding movement of the members.

10. A device of the class described comprising a pair of relatively slideable interfitting members movably mounted on a rod, means for preventing movement of either of said members on the rod, means for pro-

ducing a relative sliding movement of the members, and means for limiting the relative sliding movement of said members. 10

In testimony whereof we affix our signatures.

JOHN LEO STRANDBERG.

LARS ERIK JULIUS BLOMBERG.
